US0D1004070S

(12) **United States Design Patent** (10) Patent No.: **US D1,004,070 S**
(45) Date of Patent: ** Nov. 7, 2023

(54) **PORTABLE FAN**

(71) Applicant: **HOTECK INC.**, Taichung (TW)

(72) Inventors: **Chung-Yu Lin**, Taichung (TW);
Chia-Wei Chang, Taichung (TW);
Kai-Jen Tsai, Taichung (TW);
Min-Yuan Hsiao, Taichung (TW)

(73) Assignee: **HOTECK INC.**, Taichung (TW)

(**) Term: **15 Years**

(21) Appl. No.: **29/824,748**

(22) Filed: **Jan. 27, 2022**

(51) LOC (14) Cl. **23-04**

(52) U.S. Cl.

USPC **D23/370**

(58) **Field of Classification Search**

(57)

CLAIM

The ornamental design for a portable fan, as shown and described.

DESCRIPTION

FIG. 1 is a front, top, right perspective view of a portable fan, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded view thereof;

FIG. 9 is a front, top, right perspective view thereof in a state of use;

FIG. 10 is a rear, top, left perspective view thereof in the state of use;

FIG. 11 is another front, top, right perspective view thereof in a state of use; and,

FIG. 12 is another rear, top, left perspective view thereof in the state of use.

1 Claim, 12 Drawing Sheets
